UNITED STATES PATENT OFFICE.

FRANCIS CONST BARKER, OF DUBLIN, IRELAND.

CHROMATIC-PRINTING MACHINE.

SPECIFICATION forming part of Letters Patent No. 373,426, dated November 22, 1887.

Application filed April 21, 1886. Serial No. 199,614. (No model.) Patented in England May 12, 1885, No. 5,802.

To all whom it may concern:

Be it known that I, FRANCIS CONST BARKER, a subject of the Queen of Great Britain, residing at Dublin, Ireland, British Isles, envelope manufacturer, have invented certain new and useful Improvements in Chromatic-Printing Machines, (for which I have received Letters Patent in England, No. 5,802, dated May 12, 1885,) of which the following is a specification.

This invention has for its object an improvement on the "Magician" printing-machine, patented by E. Hely in the United States, No. 181,073, dated August 15, 1876, which improvement is applicable also to other small hand or treadle platen printing-machines used for printing envelopes, cards, tags, labels, and the like, also to those driven by steam, gas, or other power; and it consists in arrangements by which two or more colors can be printed on the one machine. It is best described by aid of the accompanying drawings, in which—

Figure 1 is a suggestive outline side view of the patent Magician machine with the present improvements attached; Fig. 2, a plan of same, showing the table at rest and printing in two colors; Fig. 3, a plan of rotating table for printing in three colors; Fig. 4, a plan of an oscillating table for printing in two colors. In all these views like letters relate to like parts. Figs. 5 and 6 are two views of a Magician machine with the improvements applied.

The machine itself is precisely similar to those used for many years by the firm of Messieurs Edward Hely & Company, envelope manufacturers, Denmark street, Dublin, of which I am the sole proprietor, except that, first, the rollers A are longer and divided into two or three lengths by deep nicks, a; second, the inking-troughs T are divided by partitions f opposite to and in correspondence with the nicks a of the rollers A, and are supplied with two or three, as the case may be, different-colored inks, one color for each division; third, in place of one die or stamp, two or three are used, as the case may be, so placed as to register correctly, one with another, on the movement of the table, and so placed as to be only inked by their respective colors.

The dies are marked B in the drawings, and

the cylinder C, to which the dies are attached, is larger, to correspond with the increased length of the rollers; or, in place of one machine divided in this way, two machines on the same shaft and worked by the same treadle can be used.

The improvements in the table are as follows: In place of or fitted upon the fixed table P, upon which the pile of blanks is placed in a Magician machine, is a movable table, D, having guides E. (Shown in Figs. 1, 2, 5, and 6.) This table is controlled by spring or other stops, F, or fences G, so as to stop always at the point required for exact registration. Where there are only two colors required, a horizontally-reciprocating table with rectilinear or with radial motion, as set forth in Fig. 4, can be used, with terminal stops or fences G; but when three or more colors are required, and therefore three or more stations, a rotary table, Figs. 2 and 3, and counterweighted drop or spring stops—such as F—or their equivalents, can be employed. A separate die, B, and inking-rollers are used for each color; or if one long roller be used it is cut at intervals to separate the colors, as already described.

If two colors are to be printed, the dies B B are placed side by side, but a little distance apart, on the stamping-cylinder, as shown in Figs. 2 and 4, and symmetrically with the center of rotation of table D, hereinafter described. The rollers are arranged in two complete sets, or one complete set cut away in the center, so that one set or side shall supply one color to one of the dies and the other set shall supply another color to another die. If there be three colors required, the rollers are divided in three, one short center set and two side sets, as set forth in Fig. 3. The dies are arranged two dies, as before, but much farther apart, and the third between them, but all three the same distance from the center of rotation, and arranged symmetrically. On the disk D two or three piles of blanks, L L, are arranged in the same manner that one set is used in the ordinary "Magician," but at equal distances from the center of rotation, and arranged symmetrically with the center J. The spring-stop F and nicks K are arranged so as to cause the table to stop at two or three points in its rotation, corresponding to the two or the three piles of

blanks. These piles, to start with, are of exactly even height. The three dies are made to exactly register.

It will be obvious that instead of the table 5 rotating or reciprocating, the machine can slide on the table; but the former arrangement is preferable. In the above, by the words "a movable table" is meant a plate moving on a fixed table, or on a pivot, J, or in guides. To 10 assist in getting an exact registration the pivot on which the table turns may be arranged to be itself adjustable by placing it on a disk-link, H, Fig. 4, or a plate or slide itself pivoted to the fixed table at I, but capable of being 15 clamped in any position, so that the center of rotation of the movable table shall be easily clamped fast after adjustment.

Referring first to Figs. 2 and 3, the mode of action is as follows: The table is moved by 20 hand or by gearing, if desired, so that for every stroke of the cylinder it shall revolve intermittently one hundred and eighty degrees in the case of two colors and ninety degrees in case of three colors for each descent of the cylinder. After each stamp, after the first one 25 or two, and in the case of the three-color machine whenever a pile comes opposite the vacant quarter, a blank fully printed with the two or three colors, as the case may be, is withdrawn. The spring-stop or its equivalent is 30 arranged to form a considerable resistance to the disk traversing past it, so that it shall stop the disk exactly at the right point through the stop entering the nick, and yet the curved or 35 V shape of the stop allows it, when a little extra pressure is applied in turning the disk, to leave the nick, and allow the disk to pass round till the next nick comes opposite the stop, when the latter falls onto it and stops the 40 table again.

The mode of operating the parts shown in Fig. 4 differs from those in Figs. 2 and 3 solely in that the table is oscillating instead of rotary, and that a single pile of blanks, L, is used, and is passed alternately under each stamp B, the table oscillating each time against the fences or stops G. This plan is not as good as the former, as there is a strain first on one side of the cylinder and then on the other 45 as each blank is used, and two strokes and two movements of the table are required for each withdrawal of a blank, instead of one only, as required with the rotary table, and this plan is only shown and a table mentioned sliding 50 in guides instead of on a pivot to prevent others claiming it as theirs.

Instead of the machine being formed with two or more dies placed on the one cylinder, it may have two or more heads, each carrying 55 a cylinder with single die, operated, preferably, simultaneously, and the table made to slide to and fro or continuously in a circular path, the envelope-blanks being brought successively under each cylinder from which they 60 are to be printed.

I claim as my invention—

1. In a chromatic-printing press, the com-

bination, with the reciprocating dies arranged to print two or more colors at once, of a movable table or support for the blanks to be 70 printed, arranged, substantially as shown, to feed the blanks successively to each die.

2. In a chromatic-printing press, the combination, with the vertically-reciprocating dies arranged to print two or more colors at 75 once, of a table or support for the blanks to be printed, movable in a plane at right angles to the movement of the die or dies.

3. In a chromatic-printing press, the combination, with the vertically-reciprocating 80 dies arranged to print two or more colors at once, of a rotating disk or table for the blanks to be printed, and means, substantially such as described, for imparting motion to the dies and table.

4. In a chromatic-printing press, the combination, with the vertically-reciprocating dies arranged to print two or more colors at once, of an intermittently-rotating disk or table for the blanks to be printed, all substantially 90 as described.

5. In combination with a machine having reciprocating dies printing two or more colors at once, a moving table or support carrying the paper blanks, and stops so arranged 95 in relative position with the dies that the blanks shall exactly register successively with each die or separately-colored portion of a die, substantially as described.

6. In combination with the reciprocating dies 100 B, each printing a separate color, a movable table, D, guides E, applied to said table for holding the blanks in proper position, and arresting devices, arranged substantially as shown, to cause the same area of the blank to stop successively under each die and thereby 105 secure exact registration.

7. In combination with reciprocating areas 110 of dies, each die supplying a different color, a fixed table, P, a table, D, for the blanks, mounted upon table P and moving a limited distance thereon, and spring-stops F, arranged, substantially as shown, to engage and stop the table D at such points as shall cause each different-colored area to register successively 115 on each blank.

8. In combination with a series of reciprocating dies, B, each supplying a differently-colored imprint, a table, D, having a controlled motion, and stops so arranged that a given area on said table shall stop successively 120 under and coincide with each die.

9. In combination with the reciprocating dies, a table, D, moving about a given center equidistant from the various dies, and carrying 125 one or more blanks of paper having their areas to be printed the same distance as the dies from the center of movement, substantially as described.

10. An intermittently-moving table, D, confined in movement to a given line and carrying a blank or blanks with their printing-surfaces on that line, in combination with a series of reciprocating dies reciprocating against 130

said blanks on that line, substantially as described.

11. The combination of the frame P, rotating table D, having two or more solitary blanks or piles of blanks, L, ranged symmetrically at equal distances from the center and at equal angles with each other, with two or more reciprocating dies, B, also placed symmetrically and at similar distances and angles to from the rotating center of the table as the

corresponding blanks or piles of blanks, substantially as described, and set forth in Figs. 2 and 3.

In testimony whereof I have signed my name to this specification in the presence of two subscribing witnesses.
